US0D1037298S

(12) **United States Design Patent** (10) **Patent No.:** **US D1,037,298 S**
(45) **Date of Patent:** **** Jul. 30, 2024**

(54) **DISPLAY SCREEN WITH A GRAPHICAL USER INTERFACE**

(71) Applicant: **Snap Inc.**, Santa Monica, CA (US)

(72) Inventor: **David Whyte**, Toronto (CA)

(73) Assignee: **SNAP INC.**, Santa Monica, CA (US)

(**) Term: **15 Years**

(21) Appl. No.: **29/877,684**

(22) Filed: **Jun. 9, 2023**

Related U.S. Application Data

(62) Division of application No. 29/788,623, filed on Jul. 6, 2021.

CLAIM

The ornamental design for a display screen with a graphical user interface, as shown and described.

DESCRIPTION

The sole FIGURE is a front view of a display screen with a graphical user interface, showing my new design. The broken lines showing an electronic device depict environmental subject matter and form no part of the claimed design. The broken lines showing a display screen illustrate portions of the article and form no part of the claimed design.

1 Claim, 1 Drawing Sheet
